his ATTORNEY

UNITED STATES PATENT OFFICE

JOSEPH REALE, OF PHILADELPHIA, PENNSYLVANIA

WASHING MACHINE

Application filed January 21, 1929. Serial No. 333,829.

In the majority of laundries the washing machines are in the form of substantially elongated cylindrical construction, the outer casing of the cylinders being stationary, 5 while the inner cylinders are capable of rotation in order to agitate the clothes and the suds. It is at present unnecessary to enter into the detail construction of any conventional type of washing machine 10 where there is a stationary cylinder and a rotating cylinder, excepting to mention that there is a moving part, in order to agitate the clothes, and to further mention that the inner cylinder is divided into a plurality of 15 compartments to receive the clothes, while the outer cylinder or casing is stationary and has a plurality of hinged covers for closing two or more compartments.

These compartments are divided to receive 20 the clothes of different customers. For instance one compartment will receive A's clothes, an adjacent compartment will receive B's clothes, the next compartment will receive C's clothes, and so on through the 25 length of the machine, for instance D's, E's and F's clothes.

In laundries an attendant may carry A's clothes in a receptacle, or by hand and when in position next to the machine the attendant's intention is to deposit clothes in A's compartment, for instance the first compartment, and since the cover closes two or more of the compartments and it must be opened to deposit the clothes, the attendant is very apt to drop some of the pieces of the clothes in the next or B's compartment and inadvertently fail to remove them, therefore causing a loss of certain pieces of A's clothes.

It is further the purpose of this invention to provide supplemental sliding covers under the hinged covers, so that when the attendant is adjacent the machine to drop in A's clothes, the attendant slides the sliding cover to a position to close the adjacent or B's compartment, thereby preventing clothes of A dropping into the adjacent compartment.

It is to be understood that the particulars herein given are in no way limitative, and

that while still keeping within the scope of the invention, any desired modification of details and proportions, as may fall within the scope of what is claimed, may be made in the construction of the appliance according 55 to circumstances.

The invention comprises further features and combination of parts to be hereinafter set forth, shown in the drawings and claimed.

In the drawings:—

Figure 1 is a view in front elevation of a washing machine of a conventional type, showing the hinged covers open.

Figure 2 is a sectional view on line 2—2 of Figure 1, but showing the hinged covers closed and illustrating the sliding cover in guides under the hinged cover.

Figure 3 is a detailed perspective view of a portion of one end of the washing machine, showing the hinged covers open and a sliding cover in position over one of the compartments.

Referring to the drawings, 1 identifies a conventional type of washing machine 75 which comprises an outer cylinder 2 and an inner rotating cylinder 3, the outer cylinder being mounted on the usual supports 4.

The inner rotating cylinder is divided into a plurality of compartments 5, 6, 7, 8, 9 and 10. However the machine may have additional compartments. The outer cylinder has an elongated opening 11 extending the full length of the machine, and hinged at 12 on the upper edge of the opening 11 is a plurality of covers 13, which are long enough and designed to close two compartments, though it is obvious that these covers 13 may be long enough to cover more than two compartments.

The inner cylinder is also provided with an elongated opening 11a, which extends the entire length of the cylinder. However the opening 11a is of less width than the opening 11 in the outer cylinder, and mounted hinged on the upper edge of the opening 11a are covers 13a. The reason for making the opening 11a of the inner cylinder of less width is for the purpose of allowing the covers 13a to be swung open, when the

covers 13 of the outer cylinder are open, in order to have access to the compartments of the inner cylinder.

The upper and lower edges of the opening 11a is provided with guide ways 14, and mounted in said guide ways are sliding covers 15. The guides 14 are so positioned in order to receive the sliding covers 15 whereby they will not interfere with the closing 10 of the hinged covers 13a, when the latter are closed.

The purpose of the sliding covers is to prevent an attendant from accidentally dropping some pieces of A's clothing in the compartment 6, when the attendant is in the act of depositing A's clothes in compartment 5. For example when the attendant approaches the machine and is in the very act of depositing A's clothes in compartment 20 5, a cover 15 is moved to uncover the compartment 5, to a position covering compartment 6, thereby preventing some pieces of A's clothing accidentally dropping into compartment 6. When the same attendant or 25 another attendant is in the act of depositing B's clothes in compartment 6, the attendant moves the cover 15 to close compartment 5 and then moves the sliding cover of the compartment 8 to close compartment 30 7, hence having the two compartments, one on each side of compartment 6 closed, so that the attendant cannot help from placing B's clothes in the compartment 6. When the attendant is in the act of placing C's 35 clothes in compartment 7 the sliding closure which has been previously moved to cover compartment 5 is moved back over compartment 6 and the sliding cover which has been previously moved over compartment 40 7 may be moved over compartment 8 so that the attendant cannot help but place C's clothing in compartment 7. These operations are continued throughout the entire length of the machine, thereby making it 45 possible that the attendants in a laundry cannot help from depositing the clothes of the rightful owner in the right compartment, and thereby prevent the loss of clothes, which is a very big item in the up- 50 keep of a laundry.

The invention having been set forth, what is claimed is:

In a washing machine, the combination with a cylindrical outer casing having an 55 elongated opening in its arcuate wall extending substantially the full length thereof, a hinged cover for said opening, an inner casing rotatably mounted in the outer casing and divided into a plurality of clothes 60 receiving compartments arranged side by side throughout the length thereof, there being an opening for each compartment and hinged covers for the compartments, each 65 constituting a closure for a plurality of openings, the inner casing adjacent the up-

per and lower edge portions of the openings to the compartments having guides extending longitudinally of the full length of the combined openings to the compartments, a plurality of covers slidable longitudinally 70 in said guides and each movable to overlie one only of said openings to prevent clothes falling therethrough while an adjacent compartment is being loaded.

In testimony whereof he affixes his signature.

JOSEPH REALE.
